UNITED STATES PATENT OFFICE.

CHARLES M. HEETER, OF BUTLER, PENNSYLVANIA.

SPUDDING ATTACHMENT FOR WELL-DRILLING MACHINES.

1,265,653.

Specification of Letters Patent.

Patented May 7, 1918.

Application filed September 14, 1916. Serial No. 120,182.

To all whom it may concern:

Be it known that I, CHARLES M. HEETER, a citizen of the United States, and resident of Butler, in the county of Butler and State 5 of Pennsylvania, have invented certain new and useful Improvements in Spudding Attachments for Well-Drilling Machines, of which the following is a specification.

One object of this invention is to provide 10 improved means for connecting the jerk and anchor lines to a spudding attachment for well drilling apparatus; the improved connection affords the attachment free pivotal movement in response to the reciprocations 15 of the drilling cable, thereby minimizing the movement of the spudding shoe on the cable, and saving the latter from much wear to which under the present practice it is subjected. A further object is to provide an improved 20 detachable connection between the spudding shoe and the shoe operating reins, whereby the shoe may be conveniently applied and removed from the cable.

In the accompanying drawings, Figure 1 25 is an elevation of a portion of well drilling apparatus, showing the improved spudding attachment in operative position. Fig. 2 is an elevation of the attachment, and Fig. 3 is a top plan of the same. Fig. 4 is a detail 30 illustrating the permanent pivotal connection between the shoe and one of the reins.

Referring to the drawings, 2 designates the derrick and 3 one of the base foundation 35 timbers thereof. At the top of the derrick is crown pulley 30, over which passes the drilling cable, one course 4 of the latter extending into the well with the drilling tools (not shown) secured thereto, and the other course 5 extending from the bull wheel 6, on which 40 the drilling cable is wound. 7 is the band-wheel shaft, carrying band-wheel 8 and crank 9, the latter adapted to connect interchangeably with jerk line 10, or pitman 11, of walking beam 12, the latter mounted on 45 samson post 13. All of the parts thus far referred to are of the usual and well known construction.

It is the usual practice to start the drilling of a well by spudding, and thereafter the 50 drilling is continued by means of the walking beam and temper screw in a manner well known in the art. For spudding, the walking beam is disconnected from the band-wheel crank shaft and the latter is utilized 55 for reciprocating a jerk line extending to a shoe that embraces that course of the drill-

ing cable that rises from the bull wheel to the crown pulley. By this means the cable is reciprocated and the tools raised and lowered to accomplish the drilling strokes. 60

The spudding shoe 15 has a V-shaped face 15' for embracing course 5 of the drilling cable, and projecting from the opposite sides of the center of the shoe are the trunnions 16 having knob-like extremities 16'. 65 At the front of the shoe is the hand-hold 17. The shoe is carried by the rein-forming bars or links 18, one of the latter formed with an eye 19 which is closed around one of the trunnions 16 and hence permanently secured 70 thereto. The other rein is formed with the extremity hook 19' which removably embraces the other trunnion, whereby the shoe may be readily applied to and removed from the cable, being conveniently manipulated 75 during that operation by handle 17. The opposite end of the reins 18 are each formed with an eye 20, and positioned therebetween is a line-connecting device 21, formed with the trunnions 22 on which the eye-formed 80 ends of the bars are secured. A pivotal connection is thus provided between the connecting device 21 and the shoe carrying reins 18, so that the latter are afforded free swinging movement in response to the reciprocation of the drilling cable, and thereby 85 minimizing the sliding, friction generating and wearing engagement of shoe 15 with the cable.

Projecting from the connecting device 21, 90 are the eye-formed arms 23 and 24, the former adapted to be secured to the jerk line 10, while arm 24 is fastened to anchor line 25 secured to the derrick floor or foundation 3. The anchor line prevents the shoe from 95 riding upwardly on the cable, and the mode of connecting the jerk and anchor lines to the reins is such that it in no way interferes with the operation of the shoe. The pivotal connection between the shoe and the reins 100 takes care of the relative movement of said parts without interfering with the effectiveness of the shoe and without causing it to slide on the cable. 105

I claim:

1. Spudding mechanism comprising a cable engaging shoe, reins to which the shoe is secured, and a connecting device pivotally carried by the reins and having two branches projecting therefrom, one branch adapted to 110 connect with a jerk line and the other branch adapted to connect with an anchor line.

2. Spudding mechanism comprising a cable-engaging shoe, reins pivotally connected at one end to the shoe, and a connecting device pivotally secured to the opposite end of the reins and provided with two line-engaging points, one for connecting a jerk line and the other for connecting an anchor line.
3. Spudding mechanism comprising a cable-engaging shoe, trunnions projecting at opposite sides of the shoe, reins mounted at one end on the trunnions, and means at the opposite end of the reins for connecting with jerk and anchor lines.
4. Spudding mechanism comprising a cable-engaging shoe, trunnions projecting from opposite sides thereof, reins provided with bearings for the trunnions, with one rein permanently secured to its trunnion and the other rein and trunnion separable for entering and withdrawing the cable, and means at the opposite end of the reins for connecting with a jerk line and with an anchor line.
5. Spudding mechanism comprising a cable-engaging shoe, reins pivotally secured thereto, and a line connecting device pivoted to the reins and having two eye-formed projections at approximately right angles to each other, one projection adapted to connect with a jerk line and the other to an anchor line.

In testimony whereof I affix my signature in the presence of two witnesses.

CHARLES M. HEETER.
